ELECTRIC CIRCUIT CONTROLLING DEVICE
OF THE THERMAL OVERLOAD TYPEEdwin N. Lightfoot, Wauwatosa, Wis., assignor to
Cutler-Hammer, Inc., Milwaukee, Wis., a cor-
poration of Delaware

Application December 9, 1933, Serial No. 701,582

9 Claims. (Cl. 200—124)

This invention relates to improvements in electric circuit controlling devices of the thermal overload type, and more particularly to such devices having the thermal overload elements thereof immersed in oil or other insulating liquid.

In the use of electric circuit controlling devices such as electromagnetically operable switches there is an increasing demand for a greater degree of protection against special conditions in service,—as where the switches are to be used in the presence of corrosive gases or vapors, or where there are explosion hazards. These conditions sometimes require submersion of the circuit controlling device in a liquid insulating medium such as oil, and when a thermal overload device is employed the same must also be submerged. Such immersion involves difficulties in handling overload devices of the thermal type which function through the development of heat in the active element with resultant tripping of the overload contacts when some definite temperature is reached.

The dissipation of heat from the source of heat (particularly such a small source as is employed in thermal overloads) in oil is much different from and greater than the dissipation of heat in air. If the usual air-operated thermal overload is placed in oil, the rapid dissipation of heat so increases its required tripping-current under continuous conditions that the ratio of its burn-out-current value to its normal-current value is so reduced as to render it commercially impractical.

My invention has for an object to provide an oil-immersed electric circuit controlling device of the thermal overload type wherein the difficulties aforementioned are obviated.

Another and more specific object is to provide an oil-immersed thermal overload device of simple and efficient character.

Another object is to provide novel means for effecting resetting of the thermal overload device after response thereof.

Other objects and advantages of the invention will hereinafter appear.

I have discovered that by placing the heat source of the thermal overload device in such an environment as to reduce the heat dissipation in oil to a permissible amount a practicable operating device will be provided. This is accomplished by locating the overload heating element in an inverted (open bottom) recess, thus providing for minimizing or reducing the convection flow of heated oil away from the heating element, where-by the heat is localized with respect to the oil

within the recess. The recess is preferably just large enough to receive the necessary parts of the thermal overload device. The walls of the recess preferably consist of a material of relatively low heat conductivity, that is to say, of molded insulating material rather than metal; and said walls are likewise preferably of considerable thickness,—both features tending to reduce or minimize conduction of heat to the main body of the oil.

When the thermal overload device is initially immersed in oil the aforementioned inverted recess will trap a quantity or bubble of air, which if allowed to remain would tend to make operation of the thermal overload device irregular. For venting of such air, I prefer to provide a small opening or passage through the upper end wall of said recess. This passage permits the air to leave the recess but does not permit a flow of oil sufficient in volume to impair the result desired and contemplated.

Where a thermal overload device of the fusible alloy type is employed, I have found that access of the oil to the fusible alloy while in its molten condition tends to reduce the useful life of the alloy. I therefore propose to so construct the container for the alloy as to minimize access of oil to the latter. This is accomplished by providing a container having a closed lower end,—instead of an open-end tube of the character employed in well known forms of thermal overload devices of the fusible alloy type adapted for operation in air.

The accompanying drawings illustrate an embodiment of my invention which will now be described, it being understood that the embodiment illustrated is susceptible of modification within the scope of the appended claims.

In the drawings, Figure 1 is a top plan view of a thermal overload device of the fusible alloy type as constructed in accordance with my invention,—a portion of said device being shown in section for clarity of illustration.

Fig. 2 is a view partly in said elevation, and partly in vertical section on the line 2 of Fig. 1.

Fig. 3 is a bottom plan view of the device shown in Figs. 1 and 2.

Fig. 4 is a vertical sectional view on the line 4—4 of Fig. 1,—certain of the parts being shown in elevation.

Fig. 5 is an enlarged vertical sectional view of certain of the elements shown at the left-hand side of Fig. 2.

Fig. 6 is a side elevation of an oil-immersed electromagnetically operable switch having my

improved form of thermal overload device associated therewith,—the oil receptacle or container being shown in section.

Fig. 7 is a fragmentary elevational view taken at right angles to the view of Fig. 6, and likewise showing the oil receptacle or container in section, and

Fig. 8 is a schematic and diagrammatic view illustrating an adaptation of my improved thermal overload device, in combination with an electromagnetically operable switch and a push-button station, to control the energization and de-energization of a suitable translating device.

Referring more particularly to Figs. 1 to 5 of the drawings, the numeral 10 designates a molded insulating base which serves as a supporting base for the several elements of my improved thermal overload device. Certain of the parts of said thermal overload device are in general quite similar to the parts disclosed in the patent of C. W. Kuhn, No. 1,894,404, dated January 17, 1933, for an electric control device. The device specifically illustrated in said Kuhn Patent No. 1,894,404 is intended for operation in air, and the same is entirely unsuited for operation when immersed in oil or other insulating liquid, for reasons hereinabove set forth.

To provide for attainment of the results contemplated by me, the base 10 is provided with a pair of substantially cylindrical recesses 11 and 12 which open to the lower surface thereof, as best illustrated in Figs. 2, 3 and 5. Located centrally within said recesses 11 and 12 and depending from the upper end walls thereof are a pair of metal cup members or cylinders 13 and 14 of like form. The upper end wall 12^d of recess 12 is provided with an opening comprising a lower cylindrical portion 12^b into which the vertically grooved or milled portion 14^a of member 14 is pressed or driven, and a relatively larger upper cylindrical portion 12^c within which the flange 14^b of hexagonal contour (Fig. 2) is adapted to seat with a press fit in a relation substantially flush with the upper surface 10^a of said base. In this manner member 14 is restrained against rotation relatively to base 10. Member 14 is provided with a closed lower end 14^c and the same is recessed as shown to provide the relatively small cylindrical portion 14^d, the relatively larger cylindrical portion 14^e, and the still larger cylindrical portion 14^f which opens to the upper surface of base 10.

A metal member 15 is provided with cylindrical portions 15^a, 15^b and 15^c respectively adapted to rotatably bear within the aforementioned portions 14^d, 14^e and 14^f. The portion 15^b is of substantially less diameter than the portion 14^e within which it bears to provide for interposition of a body or film of a fusible or eutectic alloy 16, which alloy when solid is adapted to restrain member 15 against rotation relatively to member 14.

Prior to assembling the members 14, 15 I prefer to insert within the recess in member 14 a suitable quantity of the alloy in the form of a length of wire of small cross sectional dimensions. The alloy is then fused by application of heat from a suitable source (such as a gas jet or blow-torch), and while the alloy remains in fused or molten condition the member 15 is inserted downwardly into the recess in member 14. Member 14 is provided in the wall thereof with a relatively small opening 14^g through which any excess quantity of the alloy is permitted to escape 75 to limit the height of the body of alloy within the

portion 14^e of said recess. Opening 14^g also provides for inspection or observation of the body of alloy 16. By reason of the closed lower end 14^c of member 14 the oil within which the overload device is immersed will have access to or contract with the body of the alloy 16 only at the upper end of the latter. I have found that by so minimizing the area of contact between the oil and the alloy the useful life of the latter is greatly increased, as compared with an arrangement 10 wherein the oil has access to the body of the alloy at each end thereof. Also the portion 15^b is preferably vertically grooved or milled or otherwise roughened as illustrated.

Member 15 is provided at the upper end thereof with a cylindrical portion 15^d which provides a bearing for a rotatable insulating block 17,—the insulating material of which said block is formed being preferably of the phenol-formaldehyde condensation type sold commercially under the trade name of "Bakelite". Block 17 is provided with a substantially cylindrical recess 17^a to accommodate the vertically toothed cylindrical portion 15^e of member 15,—the latter being provided with a circular flange 15^f against which the wall of recess 17^a is adapted to bear to assist in centering block 17, as best illustrated in Fig. 5. Recess 17^a is open at one side thereof to provide for engagement of a spring pawl or latch 18 with the teeth on portion 15^e,—said latch being secured to block 17 as by means of a screw 18^a having threaded engagement with a recess formed in the latter. Block 17 is provided at the side thereof opposite to latch 18 with a resilient contact member 19 having a tip riveted or otherwise secured to the free end thereof as shown at 19^a,—said tip being movable into and out of engagement with a stationary contact 20 having a wiring terminal represented by the clamping nut 20^a which threads onto the securing bolt 20^b. Member 19 is secured to block 17 as by means of a screw 19^b which threads into a recess provided in the latter. Secured to base 10 as by means of a screw 21 is a bracket 21^a having an upwardly offset horizontal portion 21^b which overlies block 17 to retain the same in bearing engagement with member 15. A similar, but right-hand, block 22 is rotatably mounted in a like manner upon the rotatable member (not shown) associated with the alloy-containing bearing member 13 (Fig. 3), said block having attached thereto a resilient contact member 23 whose tip 23^a is movable into and out of engagement with stationary contact 24 having a wiring terminal nut 24^a threaded onto securing bolt 24^b. Contact member 23 is secured to block 22 as by means of a screw 23^b. Also secured to base 10 as by means of a screw 25 is a bracket 25^a having an upwardly offset horizontal portion 25^b to retain block 22 in assembled position.

Interposed between blocks 17 and 22 at the rear ends thereof is a coiled compression spring 26 (Fig. 1) whereby block 17 is biased in a counter-clockwise direction and block 22 is biased in a clockwise direction to effect disengagement of the contact tips 19^a and 23^a from the respective contacts 20 and 24. Blocks 17 and 22 are preferably provided with integral projections or abutments which enter the respective ends of spring 26 to assist in positioning the latter,—the projection 70 on block 22 being shown at 22^b in Fig. 1, and the projection on block 17 being shown at 17^b in Fig. 4. Spring 26 is likewise provided at opposite ends thereof with straight portions (not shown) which underlie and are clamped by the heads of screws 75

^{19b} and ^{23b} to further assist in positioning the spring. In order to insure a good electrical connection between contact members ¹⁹ and ²³ I provide a suitable length of multiple-strand flexible copper wire ²⁷ the ends of which are likewise clamped by the heads of screws ^{19b} and ^{23b}. The intermediate portion of wire ²⁷ is preferably passed through the coils of spring ²⁶ to insure against fouling or excess bending thereof when in use. Blocks ¹⁷ and ²² are respectively provided with shoulders ^{17c} and ^{22c} engageable with the vertical portions of brackets ^{21a} and ^{25a} to limit the degree of movement thereof for effecting engagement of contact tips ^{15a} and ^{23a} with contacts ²⁰ and ²⁴.

The means for effecting engagement of the aforementioned contacts comprises essentially a cone-shaped cam ²⁸ which is normally positioned within a cylindrical passage ^{10b} provided in base ¹⁰,—said passage being enlarged at the lower end thereof, as indicated at ^{10c} to provide a shoulder against which a washer ^{28a} is adapted to abut. Cam ²⁸ is provided with a shank ^{28b} which is slidable through washer ^{28a}, and a coiled compression spring ^{28c} is interposed between washer ^{28a} and a second washer ^{28d} which is restrained against downward displacement as by means of a split lock washer ^{28e} of well known form. The upper end of cam ²⁸ is provided with a tapped recess to receive the lower end of a threaded adjusting rod or connector ²⁹ which is secured in adjusted relation to cam ²⁸ as by means of a lock-nut ^{29c},—the other end of said connector being adjustably secured by the lock-nut ^{29b} within the tapped recess in the lower end of an insulating member ^{30a} forming part of the pull-rod ³⁰ (Figs. 6 and 7). Thus assuming open positioning of the contacts, as shown in Fig. 1, the cam ²⁸ upon upward movement thereof is adapted to engage and spread the contact members ¹⁹ and ²³ and the blocks ¹⁷ and ²² which carry the same. The pawl ¹⁸ carried by block ¹⁷ will cooperate with the teeth ^{15e} or member ¹⁵ to retain the contact tip ^{15a} in engagement with contact ²⁰, and the corresponding parts (not shown) associated with block ²² will likewise act to retain contact tip ^{23a} in engagement with contact ²⁴. Said sets of contacts will respectively remain closed pending fusing of the alloy ¹⁶ within the container ¹⁴ or the alloy within container ¹³,—it being understood that upon fusing of the respective bodies of the alloy the blocks ¹⁷ and ²² will be free to move under the bias of spring ²⁶ to effect opening of the respective pairs of contacts.

The means for effecting fusing of the alloy within containers ¹³ and ¹⁴ comprises overload coils of resistance wire ³¹ and ³² located within recesses ¹¹ and ¹² respectively. Said overload coils ³¹ and ³² are respectively provided with terminals ^{31a}, ^{31b} and ^{32a}, ^{32b} for connection of each thereof in series in the supply lines of a translating device, such as the motor ³³ in Fig. 8. The base ¹⁰ is adapted to be positioned within a body of oil with the recesses ¹¹ and ¹² opening downwardly, as indicated in Fig. 2. It is thus apparent that portions of the body of oil will enter the respective recesses, and the heat generated by the heating coils ³¹ and ³² will be localized in said portions of the body of oil to permit transfer of the proper degree of heat to the bodies of alloy located within the containers ¹³ and ¹⁴,—the degree of diffusion of the heat so generated throughout the main body of the oil being minimized by the arrangement of said recesses ¹¹

and ¹² which prevents flow of oil from said recesses as an incident to the convection currents generated therein.

Also as aforesaid it is desirable to eliminate or vent any air or gas entrapped within the recesses ¹¹ and ¹², and I accordingly provide said recesses with relatively small passages ^{11a} and ^{12a} which extend from the upper end walls thereof and open onto the upper surface of base ¹⁰. Said passages ^{11a} and ^{12a} thus permit escape of air or gas entrapped within said recesses, whereas the same are of such small cross section as to prevent substantial upward flow or displacement of the heated oil from said recesses. While I prefer to effect venting of entrapped air by the means illustrated, it will be apparent to those skilled in the art that a similar result might be obtained by providing for tilting the base ¹⁰ or even temporarily inverting the same during or after immersion thereof within the body of oil.

In Figs. 6 and 7 I have shown my improved thermal overload device as combined with an electromagnetically operable switch of known form. Said switch, which is designated in general by the numeral ³⁴ is of the character described and claimed in the patent of C. W. Kuhn, No. 1,981,555, dated November 20, 1934, to which reference may be had for a more detailed description of said switch. Said switch in Figs. 6 and 7 is shown somewhat diagrammatically, and includes a magnet winding ^{34a}, and an armature ^{34b} controlled by said winding. Said armature carries contacts (not shown) for cooperation with suitable contacts carried upon the base of the switch. The wiring is omitted from the switch and the overload device in Figs. 6 and 7,—but the manner of wiring the various elements is shown diagrammatically in Fig. 8. The switch ³⁴ is supported by a cast metal bracket ³⁵, which bracket preferably includes a top plate ^{35a} and means ^{35b} to provide for attachment thereof to a panel, wall or other suitable support. Attached to bracket ³⁵ at the lower end thereof is a substantially U-shaped sheet metal supporting element ³⁶, to the spaced arms ^{36a}, ^{36b} of which the base ¹⁰ is attached as by means of bolts ^{36c}, ^{36d}, as illustrated, for support of base ¹⁰ in a horizontal plane with the recesses ¹¹, ¹² opening to the lower surface thereof. Base ¹⁰ is provided with end posts or projections ^{10d}, ^{10e} through which bolts ^{36c}, ^{36d} are adapted to pass. The pull-rod ³⁰ is adapted for operation in the manner aforesaid to effect resetting of the thermal overload device after response thereof.

The numeral ³⁷ designates a tank or container for a body ³⁸ of oil or other insulating liquid within which the switch and overload device are to be immersed. Tank ³⁷ is adapted to be detachably connected to cover member ^{35a} by swing-bolts or other suitable means (not shown),—the upper end of pull-rod ³⁰ having a handle ^{30b} which is removable and adjustable to facilitate assembly of the parts.

In Fig. 8 I have illustrated diagrammatically the manner of combining the electromagnetically operable switch, the overload device and a push-button station to provide for control of a translating device such as the motor ³³. The contacts of the overload device are shown set in closed position, and the push-button station is shown as comprising a normally closed push-button switch ³⁹ and a normally open push-button switch ⁴⁰. Switch ³⁴ is provided with an operating winding ^{34a}, main contacts ^{34a}, ^{34b}, ^{34c}, and auxiliary contacts ^{34e}. Thus upon closure of

push-button switch 40 a circuit is completed which may be traced from line L¹ by conductors 41 and 42 through switches 40 and 39, conductor 43 through the contacts of the overload device, and by conductor 44 through said winding 34^a to line L². Switch 34 thus responds to complete the circuit for motor 33. The auxiliary contacts 34^b of switch 34 upon closure thereof shunt the push-button switch 40 to provide a maintaining circuit for winding 34^a. The circuit of winding 34^a will be maintained pending manual opening of push-button switch 39 or automatic opening of one or both of the pairs of overload contacts 19^a, 20 or 23^a, 24 due to the aforescribed heating effect of the overload coils 32, 31, respectively. The push-button station is shown diagrammatically as being provided with a housing or enclosure 45 of the gas-tight or explosion-proof type. Enclosures of this character are well known in the art, and further description thereof is deemed unnecessary. The arrangement of course will be such as to provide for operation of the push-button switches 39, 40 by means accessible from the exterior of the housing. The push-button switches 39, 40 may if desired be located at a point remote from the switch 34 and the overload device, in which event an explosion-proof casing for said push-button switches may be considered unnecessary.

30 While I have described my invention with specific reference to thermal overload devices of the fusible alloy type, it is to be understood that certain features herein disclosed are equally applicable to other types of thermal overloads, such as the thermostatic metal type, the hot-wire type, the expansion bellows type, etc.

What I claim as new and desire to secure by Letters Patent is:

1. In a device of the character described, in combination, a container, a body of insulating liquid in said container, an electro-thermally responsive circuit breaker immersed in said liquid, said circuit breaker including a base having a recess opening downwardly, and a thermally responsive element and an electric heating element located within said recess, the walls of said recess acting to localize the heat generated by said heating element to that portion of the body of liquid located within said recess.
- 50 2. In a device of the character described, in combination, a container, a body of insulating liquid in said container, an electro-thermally responsive circuit breaker immersed in said liquid, said circuit breaker including a base having a recess formed in the lower surface thereof, a thermally responsive element and an electric heating element located within said recess, the walls of said recess acting to localize the heat generated by said heating element to that portion of the body of liquid located within said recess, and means for effecting release of air entrapped within said recess.
- 65 3. In a device of the character described, in combination, a container, a body of insulating liquid in said container, an electro-thermally responsive circuit breaker immersed in said liquid, said circuit breaker including an insulating base having a recess in the lower surface thereof, a thermally responsive element and an electric heating element located within said recess, the walls of said recess acting to localize the heat generated by said heating element to that portion of the body of liquid located within said recess, and the upper end wall of said recess having a relatively small passage extending there-

through to provide for automatic venting of any air or gas entrapped within said recess while preventing any substantial flow of liquid from the latter.

4. In a thermal overload device, in combination, 5 a body of insulating liquid such as oil, an insulating base to be totally submerged in said oil, said base having a recess formed therein and opening to the lower surface thereof, a hollow metal member having a closed lower end extending 10 downwardly from the upper end wall of said recess, the upper end of said member being non-rotatably secured to said base and opening to the upper surface of the latter, a metal member having a body of solder interposed between the same 15 and said hollow member and adapted when solid to prevent rotation of said metal member, means tending to effect rotation of said metal member in one direction, and an electric wire heating coil located within said recess and surrounding said 20 hollow member, said coil when energized being adapted to heat the oil within said recess to effect a corresponding degree of heating of said body of solder, the walls of said recess acting to prevent substantial displacement of the heated oil 25 therefrom under the influence of convection currents generated therein.

5. In a thermal overload device of the character described, in combination, a molded insulating base having a substantially cylindrical recess 30 opening to the lower surface thereof, a thermally responsive unit comprising a hollow metal member having a closed lower end, said member being non-rotatably supported by and depending from the upper end wall of said recess and having 35 its upper end opening to the upper surface of said base, a shank member insertable downwardly into said hollow member and having a rotatable bearing engagement with the latter, means comprising a quantity of eutectic alloy interposed between said shank member and said hollow member to normally restrain the former against rotation with respect to the latter, means biasing said shank member for rotation thereof in one direction, a body of insulating liquid with 40 in which said thermal overload device is submerged, and an electric heating element located within said recess in spaced relationship to said cylindrical member, said recess having a relatively small passage extending upwardly through 45 the upper end thereof, said passage providing for automatic venting of any air or gas entrapped within said recess while preventing substantial displacement of said liquid from said recess under the influence of convection currents generated 50 therein.

6. In a thermal overload device of the character described, in combination, a molded insulating base having a cup-shaped recess opening to the lower surface thereof, a thermally responsive unit comprising a substantially cylindrical member having a closed lower end, said member being non-rotatably supported by and depending from the upper end wall of said recess, an electric wire heating element located within said recess 60 in spaced relationship to said cylindrical member, a toothed wheel exposed upon the upper surface of said base and having a shank extending downwardly into said cylindrical member, means comprising a fusible medium interposed between said shank and said member to normally restrain the former against rotation, a stationary contact and a movable contact, said movable contact being biased away from said stationary contact, a pawl associated with said movable contact and en- 65 75

- gageable with said toothed wheel to restrain said movable contact against movement under its bias pending a given degree of heating of said fusible medium, a body of insulating liquid within which
5. said thermal overload device is submerged, a portion of said body of liquid being adapted to fill said recess, and the walls of said recess acting to prevent substantial displacement of said portion of said body of liquid under the influence of convection currents generated therein to facilitate transmission of said heat to said fusible medium.
7. In a thermal overload device of the character described, in combination, a molded insulating base having a cup-shaped recess opening to the lower surface thereof, a thermally responsive unit comprising a substantially cylindrical member having a closed lower end, said member being non-rotatably supported by and depending from the upper end wall of said recess, an electric wire heating element located within said recess in spaced relationship to said cylindrical member, a toothed wheel exposed upon the upper surface of said base and having a shank extending downwardly into said cylindrical member, means comprising a fusible medium interposed between said shank and said member to normally restrain the former against rotation, a stationary contact and a movable contact, said movable contact being biased away from said stationary contact, a pawl associated with said movable contact and engageable with said toothed wheel to restrain said movable contact against movement under its bias pending a given degree of heating of said fusible medium, a body of insulating liquid within which said thermal overload device is submerged, a portion of said body of liquid being adapted to fill said recess, the walls of said recess acting to prevent substantial displacement of said portion of said body of liquid under the influence of convection currents generated therein to facilitate transmission of said heat to said fusible medium, and a pull-rod extending upwardly through and beyond said body of insulating liquid to provide for resetting of said overload device and consequent re-engagement of said contacts after response of the former.
8. In a system of the character described embodying an electric translating device, an electromagnetically operable switch to control energization and de-energization of said translating device, a container, and a body of insulating liquid located within said container, said switch and the electromagnetic means therefor being
10. submerged within said body of liquid, in combination, an electrothermally responsive overload device also submerged within said body of liquid and adapted upon response thereof to effect interruption of the energizing circuit of said switch, said overload device including a base having a recess opening downwardly, a thermally responsive element and an electric heating element located within said recess, and manually operable means extending upwardly through said body of liquid and accessible from the exterior of said container for effecting resetting of said overload device after response thereof.
15. In a system of the character described embodying an electric translating device, an electromagnetically operable switch to control energization and de-energization of said translating device, a container, a body of insulating liquid located within said container, said switch and the electromagnetic operating means therefor being submerged within said body of liquid, an electro-thermally responsive overload device, a push-button station located at a point spaced from said container, said station including a normally open push-button switch and a normally closed push-button switch, said normally open push-button switch when closed being adapted to cooperate with said normally closed push-button switch and said overload device to initially complete the energizing circuit of said electromagnetically operable switch, and said normally closed push-button switch being operable at will independently of said overload device to effect interruption of the energizing circuit of said electromagnetically operable switch, the combination wherein said electro-thermally responsive overload device is also submerged within said body of liquid and adapted upon response thereof to effect interruption of the energizing circuit of said switch, said overload device including a molded insulating base having a recess opening to the lower surface thereof, a thermally responsive element and an electric heating element located within said recess, manually operable means extending upwardly through said body of liquid and accessible from the exterior of said container for effecting resetting of said overload device after response thereof, and an explosion-proof housing within which the contacts of said push-button switches are enclosed.

EDWIN N. LIGHTFOOT.

Certificate of Correction

Patent No. 2,027,541.

January 14, 1936.

EDWIN N. LIGHTFOOT

It is hereby certified that errors appear in the printed specification of the above numbered patent requiring correction as follows: Page 1, second column, line 44, for the word "said" read *side*; page 2, second column, line 5, for "contract" read *contact*; page 3, first column, lines 14 and 44 respectively, for "15*" read *19**; same page and column, line 34, strike out the word "the"; page 4, first column, line 24, for the syllable "bush-" read *push-*; and that the said Letters Patent should be read with these corrections therein that the same may conform to the record of the case in the Patent Office.

Signed and sealed this 19th day of May, A. D. 1936.
